CLAIM

The ornamental design for a fishing box, as shown and described.

DESCRIPTION

FIG. 1 is a front, left and top perspective view in the used configuration with the five parts assembled together of an fishing box, showing my new design;

FIG. 2 is a rear, right and bottom perspective view in the used configuration with the four parts assembled together of an fishing box;

FIG. 3 is a front, left and top perspective view of the first part of the fishing box;

FIG. 4 is a rear, right and bottom perspective view thereof;

FIG. 5 is a front view thereof;

FIG. 6 is a rear view thereof;

FIG. 7 is a left side view thereof;

FIG. 8 is a right side view thereof;

FIG. 9 is a top plan view thereof;

FIG. 10 is a bottom plan view thereof;

FIG. 11 is a front, right and top perspective view of the second part of the fishing box;

FIG. 12 is a rear, left and bottom perspective view thereof;

FIG. 13 is a front view thereof;

FIG. 14 is a rear view thereof;

FIG. 15 is a left side view thereof;

FIG. 16 is a right side view thereof;

FIG. 17 is a top plan view thereof;

FIG. 18 is a bottom plan view thereof;

FIG. 19 is a front, right and top perspective view of the third part of the fishing box;

FIG. 20 is a rear, left and bottom perspective view thereof;

FIG. 21 is a front view thereof;

FIG. 22 is a rear view thereof;

FIG. 23 is a left side view thereof;

FIG. 24 is a right side view thereof;

FIG. 25 is a top plan view thereof;

FIG. 26 is a bottom plan view thereof;

FIG. 27 is a front, right and top perspective view of the fourth part of the fishing box;

FIG. 28 is a rear, left and bottom perspective view thereof;

(Continued)

FIG. 29 is a front view thereof;
FIG. 30 is a rear view thereof;
FIG. 31 is a left side view thereof;
FIG. 32 is a right side view thereof;
FIG. 33 is a top plan view thereof;
FIG. 34 is a bottom plan view thereof;
FIG. 35 is a front, right and bottom perspective view of the fifth part of the fishing box;
FIG. 36 is a rear, left and top perspective view thereof;
FIG. 37 is a front view thereof;
FIG. 38 is a rear view thereof;
FIG. 39 is a left side view thereof;
FIG. 40 is a right side view thereof;
FIG. 41 is a top plan view thereof; and,
FIG. 42 is a bottom plan view thereof.
The broken lines shown in the drawings illustrate portions of the fishing box that form no part of the claimed design.
